UNITED STATES PATENT OFFICE.

CLARENCE H. REESE, OF GWYNBROOK, MARYLAND.

CLEANER FOR TYPE-WRITING MACHINES.

SPECIFICATION forming part of Letters Patent No. 745,238, dated November 24, 1903.

Application filed February 10, 1903. Serial No. 142,814. (No model.)

To all whom it may concern:

Be it known that I, CLARENCE H. REESE, a citizen of the United States, residing at Gwynnbrook, in the county of Baltimore and State of Maryland, have invented new and useful Improvements in Cleaners for Type-Writing Machines, of which the following is a specification.

This invention relates to a type-cleaner for type-writing machines for use in connection with machines in which the type-carrying bars or levers are arranged in basket form and accessible through the medium of an upper opening defined by the basket.

15 The present type-cleaner is of such form as to permit its ready application to and operation on type disposed in approximately elliptical form and to equally bear upon all the type-faces and simultaneously remove dirt or grit from the latter. By having the direct cleaning member of the improved device bear equally on all the type-faces the least disturbance of the alinement of the type is avoided and at the same time a thorough cleaning operation ensues.

Broadly stated, the invention contemplates the use of a brush having a peripheral contour corresponding to that of the series of type-faces with which it is adapted to coöperate and means for holding the brush within the basket of a type-writing machine with such degree of positiveness that it may be vertically reciprocated to effect a thorough cleaning and polishing of the type-faces.

30 The invention also contemplates the use of a cleaning-brush having a contour similar to that of the series of type with which it is placed in engagement and also such dimensions as to bring the brush members with equal pressure against the type-faces.

The invention further consists in the details of construction and arrangement of the several parts which will be more fully herein-after described and claimed.

45 In the drawings, Figure 1 is a longitudinal vertical section of a portion of a type-writing-machine basket and the improved cleaner in operative position in relation thereto. Fig. 2 is a perspective view of the cleaner.

50 Similar numerals of reference are employed to indicate corresponding parts in the views.

The numeral 1 designates a frame compris-

ing an upper plate 2, having openings 3 at diametrically opposite points. Secured to and depending from the said plate 2 is a series of resilient arms 4, which are outwardly inclined toward their lower extremities and curved inwardly at their upper portions. The arms 4 are diametrically disposed, and to their lower terminals elongated pressure members in the form of longitudinally-curved straps 5 are secured. The pressure members are arranged to form a substantial rectangle with curved sides, two of the members being longer than the remaining pair, as clearly indicated by Fig. 2. Two of the arms 4 are continued above the plate 2 to form a guide 6, and in the top horizontal member 7 of the latter openings 8 are constructed and arranged in alinement with the openings 3 in the plate 2 below.

A handle 9 has its opposite members reciprocatingly mounted in the top member of the guide and plate 2 and freely movable in the openings 3 and 8 of the said respective parts. 75 The lower terminals of the handle are screw-threaded and inserted through a brush-body 10 of elliptical form, the said handle-terminals being held in positive engagement with the body by nuts 11 and 12, respectively bearing 80 against the lower and uppersides of said body, thereby always maintaining the latter in positive position on the members of the handle. The brush-body can be readily removed and reapplied or another similar device substituted for one that has become worn. Projecting outwardly from the body 10 are a plurality of bristles 13, which form a brush 14, said bristles all having an equal length and terminally trimmed or cut to conform exactly 90 to the contour of the periphery of the body 10 and to the normal arrangement or disposition of the type-faces within certain makes of type-writing machines.

In applying the improved device the upper 95 opening leading to a type-basket is cleared by throwing the ribbon back and out of the way, and the arms 4 are compressed to permit them to pass down through the said opening and then released to have them frictionally engage the type-levers, the cleaner as an entirety being depressed until the brush 14 engages the type-faces, as clearly shown by Fig. 1. While in this position the operator

holds the cleaner at the upper portion with one hand and vertically reciprocates the handle 9 with the other hand, thereby causing the brush 14 to regularly move over the type-faces with equal pressure on all of the latter.

As soon as the cleaning operation is completed the arms 4 are again compressed and the device removed from the type-basket.

As heretofore indicated, the exertion of equal pressure on all the type-faces by the brush 14 at the same time will overcome any tendency to throw the type out of alignment or bend the type bars or levers, and, furthermore, the type-faces can be expeditiously cleaned as well as polished. In some instances the cleaner may be furnished elliptical brushes of the form set forth having varying dimensions, so as to adapt the same for use in connection with type-baskets correspondingly differing in dimensions; but as the scale of certain classes of machines having the type-faces normally disposed in elliptical form is uniform one brush of a corresponding size will be effective in cleaning the type-faces of such machines.

The improved cleaner overcomes the disadvantages of individually removing dirt and sediment or grit from type-faces, and the operator can readily use the cleaner without soiling the hands.

The arms 4, carrying the pressure members at their lower ends, are materially advantageous in view of the fact that the entire complement of the type-bars of a type-writing machine are engaged by the said pressure members, and all the type will be held firmly in place regardless of the thickness of the brush or the quality of the bristles of the latter. Moreover, the plate 2 forms a shoulder upon which downward pressure may be exerted to cause the pressure members to firmly engage the type-bars, the said shoulder being readily accessible at the top of the basket, and conjointly operating with this structure as a means for firmly holding the attachment in applied position is the guide 6, which will serve as a grip to steady the device while the brush is vertically reciprocated. By maintaining the attachment in immovable position within the type-basket and having the pressure members engage the type-bars above the type of the latter the brush will work with even pressure on all of the type and without bearing stronger on one side than the other. In devices of this class, where springs are used to return the parts to normal position or assist in their operation, many disadvantages have been observed, and, among others, may be mentioned that in such devices the downward stroke requires not only sufficient power to overcome the resistance of the brush against the type, which will be increased by thickening the brush, but must also overcome the resistance of the spring, which must also have sufficient power to overcome the same brush resistance in an upward direction, and this amount of pressure

upon the type-bars, especially when distributed to only two sides, must have a tendency to force the type out of alignment.

A further advantage of having the pressure members at the sides and ends of the cleaner is that the latter is prevented from wabbling or having unsteady position within the type-basket when applied. If the pressure devices were only on the sides, or if the sides were clear and the ends supplied with such pressure members, it is obvious that the cleaner would have to be held in a particular manner by the operator to prevent it from moving out of place when the brush was reciprocated. The present improved construction, embodying pressure devices surrounding the device as an entirety or located at the sides and ends, dispenses with the use of a thick clumsy brush and makes it possible to use a neat thin brush. Moreover, the arrangement of the frame of the cleaner as set forth permits it to project above the upper portion of the type-writing machine, which allows the arms or pressure members to be sufficiently compressed to clear the ribbon-guards usually found at each end of the top of the type-basket, and, as before intimated, the end pressure members hold the frame in fixed position within the type-basket.

Having thus fully described the invention, what is claimed as new is—

1. A cleaner for type-writing-machine type freely insertible in and withdrawable from the upper open portion of a type-basket, consisting of a frame having an upper shoulder and grip means normally projected above the upper open end of the type-basket when the cleaner is applied, and arms depending from the shoulder and carrying side and end pressure members, and a brush reciprocatingly mounted within the area of the pressure members and having a contour corresponding to the normal arrangement of the type, the pressure members being movably held and surrounding an area greater than the maximum dimension of the brush and located above the latter whereby all the type-bars comprising the basket will have an equal pressure applied thereto above the type.

2. A cleaner for type-writing-machine type freely insertible in and withdrawable from the upper open portion of a type-basket comprising an upper horizontal plate with arms depending therefrom, a portion of the arms being continued above the plate to form a grip, the arms carrying at their lower extremities side and end pressure members to engage type of the bars of the basket above the type, a brush conforming to the contour of the type when in normal position and freely movable upwardly within the confines of the pressure members, and means connected to the brush vertically slidale through the plate and the grip whereby the brush may be operated, the said means having applied thereto an equal movement in opposite directions to clean the type-faces.

3. A cleaner for type-writing-machine type freely insertible in and withdrawable from the upper open portion of a type-basket and consisting of a vertically-reciprocable brush conforming in contour to the normal position of the type and having a movement in opposite directions without resistance, a frame having depending side and end pressure members to engage the type-bars above the type to exert an equal pressure on said bars throughout the entire complement of the latter, and

means connected to the brush and movable vertically through the frame, the brush being movable within the confines of the pressure members and operative in opposite directions 15 solely by manual power.

In testimony whereof I affix my signature in presence of two witnesses.

CLARENCE H. REESE.
